UNITED STATES PATENT OFFICE.

ANDREW F. LAPHAM, OF NEW YORK, N. Y.

WASHING-MACHINE.

Specification of Letters Patent No. 30,331, dated October 9, 1860.

To all whom it may concern:

Be it known that I, ANDREW F. LAPHAM, of the city, county, and State of New York, have invented a new and useful Improvement 5 in Washing-Machines, which is fully and clearly set forth in the following specification, including the accompanying drawing, with letters of reference marked thereon and making part of the same.

10 The drawing exhibits a side parallel view of a vertical section taken or drawn lengthwise through the center of the whole apparatus.

a represents the frame.

15 *b* represents the axle, or axis upon which and around which the washing apparatus is made to revolve.

c is the crank and handle.

20 *d* is an air tight cylinder similar to a barrel in shape and construction.

25 *e* are transverse ribs which are attached to the inner surface of the cylinder *d*, and extends around the entire inner circumference of the cylinder *d*. These ribs *e* form— when the apparatus is in motion—a revolving 30 reversible double inclined cylindrical ribbed washing board, in consequence of the axle *b* being placed at a right angle with the long diameter of the air tight cylinder *d*, which arrangement causes the cylinder to revolve endwise instead of sidewise, which has been the custom heretofore in washing machines.

f are spherical balls, which may be made of wood or smooth stone of about two to 35 four inches diameter and requiring about one to two dozen, and are thrown loose into the cylinder *d*.

g, is the air tight lid or door through 40 which the clothes are put into the machine.

The operation of washing consists in putting the clothes, balls and water all together in the cylinder *d* and close the air tight lid *g* and revolve the cylinder *d* endwise around the axle *b*, which operation causes 45 the clothes to rapidly change their relative position with the loose balls *f*, while the whole is being rolled up and down upon the transverse ribs *e* which—as previously explained—forms a revolving reversible 50 double inclined cylindrical washing board, the whole operation being simple and effective.

Having thus clearly described the construction and operation of my invention 55 what I claim as new and desire to secure by Letters Patent of the United States is—

The air tight cylinder *d*, when constructed with transverse circular ribs *e* as described and arranged to revolve endwise together with the loose balls *f*, substantially as set forth.

ANDREW F. LAPHAM.
